UNITED STATES PATENT OFFICE.

GEORGE U. BRAKE AND CHARLES HOLLMANN, OF FORT WAYNE, INDIANA.

TUBE-WINDING MACHINE.

Application filed October 16, 1925. Serial No. 62,757.

To all whom it may concern:

Be it known that we, GEORGE U. BRAKE and CHARLES HOLLMANN, citizens of the United States, residing at Fort Wayne, in the county of Allen and State of Indiana, have invented new and useful Improvements in Tube-Winding Machines, of which the following is a specification.

The invention relates to machines by which to wind rectangular tubes. There is a demand for rectangular paper tubes, for core purposes and for boxes, it being evident, in the case of boxes, that more of them may be packed in a container than where they are cylindrical.

The object of our invention is to provide a simple machine upon which paper tubes may be efficiently wound automatically.

Another object is to provide the machine with means by which the tube is continuously removed therefrom as it is formed.

Other objects and advantages will appear hereinafter.

The invention consists in a revoluble mandrel, square or rectangular in cross-section, upon which the paper is wound in selected plies and rotating means engaging the winding for continuously advancing it along the mandrel and continuously discharging the finished rectangular tube therefrom.

An embodiment of the invention is illustrated in the accompanying drawings in which,

Figure 1 is an elevational view of a machine embodying the invention; Fig. 2 a cross-section of the feeding mechanism on line 2—2 of Fig. 1 and Fig. 3 a detail view of the frictional driving means.

Referring to the illustrative embodiment of the invention, 1 is the base of the machine having thereon the two upstanding standards or end members 2, 3. The standard 2 is slidably secured to the base and carries a bearing 4 and member 3 carries a bearing 5. A mandrel 6 is revolubly supported in the bearing 4, the mandrel being rectangular in cross section. 7 represents one or more spools of paper that are revolubly supported so that the strip or strips 8 may be fed to the mandrel in spiral manner. Any number of strips 8 may be fed depending upon the number of plies of paper, or thickness desired for the tube. The mandrel, of

course, will be of the size required to form the desired inner diameter of the tube to be made.

A gear 9 is secured to the mandrel and meshes with the pinion 10 secured to a shaft 11^a that is revolubly mounted in the standard 2, and one-half of a clutch 11^b is secured to the end of this shaft, the other half of the clutch being secured to the end of a shaft 11 supported in the standard 3 and having a bearing 1^a formed on the base 1. A pinion 12 is secured to the shaft 11 and meshes with a gear 13 that is fixed on a sleeve 14 revolubly mounted in the bearing 5. The free end of the mandrel passes freely through this sleeve.

A frame 15 is secured to the inner end of the sleeve 14 and consists of end walls or plates 16, 16^a, each having an opening 17 therein through which the mandrel freely passes, and top and bottom plates 18 and 19. A suitable number of shafts 20, 20' are revolubly mounted in the plates 18 and 19 upon opposite sides of the mandrel and upon each of them is adjustably secured a feed roller 21, 21'. Above the rollers 21, 21' and slidably mounted on the shafts 20, 20' are other feed rollers 22, 22', springs 23 on the shafts engaging the upper side of the feed rollers 22 and 22' and the top member 18 for supplying tension to the feed rollers 22, 22' and causing them to frictionally engage the tube 24. The lower rollers 21, 21' are adjusted with the desired clearance relatively to the mandrel so that they will frictionally engage the tube.

25 represents an electric motor having 90 a bevel gear 26 secured to its shaft 25^a. This gear meshes with a gear 27 secured to the lower end of a revolubly mounted shaft 28. The shaft 28 is designed to drive the shafts 11, 11^a. One form of driving connection for the shafts 11, 11^a is shown in Fig. 3 in which a gear 29 is secured to the shaft 28 and meshes with a gear 30 secured to a shaft 31 suitably supported at 31^a on the frame. A friction wheel 32 is adjustably secured to the shaft 31 and engages a disk 33 secured to the shaft 11.

A similar friction wheel 34 is similarly driven by the shaft 28 and engages a disk 35 secured to a shaft 36 supported in a bearing 37 formed on the standard 3. A gear

38 is secured to the shaft 36 and meshes with a gear 39 secured to a shaft 40 mounted in a bearing 41 carried by the standard 3. A pinion 42 is secured to this shaft 40 and meshes with a gear 43 mounted on the exterior of the bearing 5. This gear 43 is also internally threaded and this internal gear 43' is engaged by a pinion 44 secured to a shaft 45 revolubly mounted in the brackets 46 depending from the frame 15. A plurality of worms 47 are secured to or formed on the shaft 45 and mesh respectively with worm wheels 48 secured to the lower ends of the shaft 20, and with worm wheels 49 on the lower ends of the shafts 20' on the opposite side of the mandrel. The electric motor is illustrative of a driving means for the mechanism and it is seen that it drives the shaft 28 which in turn through the shafts 11, 11' and the pinion 10 and gears 9 drive the mandrel at the selected speed. The shafts 11, 11' also, through the pinion 12, the gear 13 and the sleeve 14 drive the frame 15, the mandrel and frame 15 rotating in the same direction and preferably at the same speed. The shaft 31 and the gearing connecting it to the worm-carrying shaft 45 cause the shafts 20' to rotate clockwise and the shafts 20 to rotate counter-clockwise (Fig. 2) to rotate the feed rollers in proper opposite directions to continuously move the tube along the mandrel as that tube is formed thereon, the speed of rotation of the feed rollers being regulated to synchronize with the speed of rotation of the mandrel.

The paper strips 8 are guided in any suitable manner upon the mandrel so as to form a complete wall. Initially the standard 2 will be released and moved outwardly along the base to move the mandrel longitudinally a sufficient distance to enable the paper strips to be wound on a sufficient portion of the mandrel to form a length of tube that will, when the standard and mandrel are returned to normal position, be engaged by all the feed rollers. Thereafter as the winding of the tube continues the rotating feed rollers continuously move the tube along the mandrel and toward and off the free end of the same. The tube may be cut in suitable manner into any lengths desired.

In order to facilitate the movement of the finished tube on the mandrel, we prefer to slightly reduce the diameter of the mandrel from a point adjacent the first set of feed rollers met by the tube to the free end of the mandrel. This reduction in diameter is very slight only, say two thousandths of an inch.

It is now seen that we have devised a machine in which the tube is advanced continuously toward the discharge end of the mandrel and hence no delay is occasioned by the removal of the finished tube.

Any desired shape of mandrel may be used, the feeding mechanism being applicable to any selected or desired form of tube to be built; hence, we do not wish to be limited to the precise form of mandrel described and illustrated nor to the specific form of feeding mechanism described above.

What we claim is:

1. In a tube winding machine, the combination of a longitudinally movable and revolubly mounted mandrel, a revoluble support, feeding members revolubly mounted on the support and adjacent to the mandrel and adapted to engage the tube being formed on the mandrel and continuously move it along the mandrel, means to rotate the mandrel and the frame in synchronism and independent means to synchronize the rotation of the feeding members with the mandrel.

2. In a tube winding machine, the combination of a revolubly mounted mandrel upon which to wind a tube, a plurality of feeding members revolubly mounted adjacent to the mandrel and adapted to engage and continuously move the tube as wound, the mounting of the feeding members being revoluble, means to cause the mandrel and the said mounting to rotate in unison and means to regulate the speed of rotation of the feeding members independently of the mandrel and the mounting.

3. In a paper tube winding machine, a revolubly mounted angular mandrel having one free end and upon which mandrel strips of paper are adapted to be wound to form a tube, and means to continuously remove the tube from the mandrel as it is formed consisting of a revolubly mounted frame and a plurality of feeding members revolubly mounted on the frame adjacent to the mandrel and adapted to engage the tube and continuously move it along the mandrel toward the free end thereof and means to regulate the speed of rotation of the feeding members independently of the rotation of the frame.

4. In a paper tube winding machine, a revolubly mounted rectangular mandrel having one free end and upon which mandrel strips of paper are adapted to be wound to form a tube, and means to continuously remove the tube from the mandrel as it is formed consisting of a revolubly mounted frame through which the mandrel loosely projects, a plurality of shafts revolubly mounted in the frame upon opposite sides of the mandrel, feed rollers adjustably secured to the shafts and adapted to frictionally engage the tube for moving the tube along the mandrel toward the free end thereof, means to rotate the mandrel and the frame uniformly, means to cause the feed roller shafts on one side of the mandrel to rotate in a direction opposite to that on the other

side and means to regulate the speed of rotation of the feed roller shafts independently of the rotation of the frame.

5. In a paper tube winding machine, a longitudinally movable and revolvably mounted angular mandrel, means to feed paper strips to the mandrel to form a tube thereon, a revolvably mounted frame about the mandrel, means to rotate the mandrel and frame in synchronism, a plurality of feeding

on the frame and adapted to engage the tube formed on the mandrel and an adjustable friction means to drive the feeding members at speeds in synchronism with the speed of rotation of the formed tube to cause the tube to continuously move longitudinally on the mandrel. 15

In witness whereof we have hereunto set our hands this 14th day of October, 1925.

GEORGE U. BRAKE.
CHARLES HOLLMANN.
